(57) **CLAIM**

The ornamental design for a modem, as shown and described.

DESCRIPTION

FIG. 1 is a top view of a modem;
FIG. 2 is a right side view thereof;
FIG. 3 is a left side view thereof;
FIG. 4 is a front view thereof;
FIG. 5 is a back view thereof;
FIG. 6 is a bottom view thereof; and,
FIG. 7 is a front perspective view thereof.
Gradations in tone throughout the views are solely intended to represent surface shading.
